MECHANIZED MOUNT FOR THE ASSEMBLY
OF FLAT PRINTING PLATES

John Murray, Chobham, England

Application January 29, 1944, Serial No. 520,248
In Great Britain November 24, 1942

2 Claims. (Cl. 101—383)

This invention has for its object the more expeditious assembly of printing plates on flat beds of printing machines used mainly in the printing of books, magazines, and the like, in order to decrease the number of preparatory or standing hours of the machine, and thus increase the operating or producing period of the life of the machine.

The material of which the beds are made may be metal, or metal in combination with thermoplastic or thermo-setting material.

A complete working mount or bed is made up by the assembly of unit sections each of eight pages to the size required for the sheet to be printed therefrom.

One popular size of printed sheet is forty by thirty inches, requiring four unit sections, making thirty two pages. Another size is sixty by forty inches, requiring eight unit sections for sixty four pages.

Each eight-plate or unit section of the mount comprises four sub-sections which are assembled in series into a metal frame-work. Each sub-section provides a surface for two plates at the required height. On the under surface of each sub-section are T slots which accommodate and form guideways for racks which operate gears for actuating plate-clamping dogs.

A mechanized mount for the assembly of flat printing plates, according to the invention, is illustrated diagrammatically in the accompanying drawings in which Figs. 1 and 1^a together constitute a plan view of an eight-page or unit section. Fig. 1^b is a longitudinal section of a sub-section of the mount. Fig. 2 is an end elevation of the mount. Figs. 3 and 3^a are a detail plan view and an end view, respectively, of a sub-section. Fig. 4 is an elevation of a pair of cross-bars. Figs. 5 and 5^a are a vertical section and a plan, respectively, of a gear unit. Figs. 6 and 7 are fragmentary detail views. Fig. 8 is a plan of a modified form of sub-section.

Referring to the drawings, the eight-plate or unit section of the mount shown comprises four sub-sections A, B, C, D, respectively, which are assembled in series into a metal frame 9, 10, 12. Each sub-section provides a surface for two plates such as P at the required height. On the under surface of each sub-section are three T slots 5, which may be machined or may be die cast in the sub-sections of the mount. The top portions of the T slots 5 accommodate and form guideways for racks 6 which mesh with gears 7 adapted to actuate plate-clamping dogs 8.

The frame comprises two parallel side bars 9

fitted into slots in a tie bar 10 at one end, and fixed with screws 11 or other means. The other ends of the bars 9 are fitted into slots in a tie bar 12 provided with slots for the passage of the racks 6, and with tapped holes into which are fitted screws 13 by which the racks 6 are adjustable. The sides of each subsection are formed to fit over the side bars 9. The distance between the outer edges of the side bars 9 is equal to the width of a subsection, namely ten inches or thereabouts.

Three pairs of crossbars 14, 15, 16 are located on, and attached to the side bars 9, one cross-bar of each pair being attached above the side bars, and the other below the side bars 9. In 15 each of the four equal spaces thus formed between the cross-bars is a subsection. When the unit section is assembled and viewed from the end which supports the adjusting screws, there are four plates on the left hand, and four plates 20 on the right hand, of the centre line of the unit section.

The means by which the eight dogs 8 which determine and maintain the position of the four plates on each side of the back marginal space 25 or centre line of the eight page section are actuated comprises four sets of multi-gear mechanisms, conveniently, triple-gear or twin-gear mechanisms.

For a triple-gear mechanism there are, as 30 shown in Figs. 1-7, three holes or bearings 17, 18, 19 in each subsection located on the centre line, into which are fitted the gear units 7 which are assembled in bosses or journals 20 supported with their axes vertical. The gear units are located as follows: The centre of the mid-gear is on the centre line at or near a point half-way between the top and bottom of the page. The centres of the other two gears are also located on the centre line, one on each side of the mid-gear, at a distance equal to the desired length of the dogs. On 35 each of the journals of the mid-gears in the four triple-gear groups two eccentric pins 20', 21 are attached, one at twelve o'clock, and the other at six o'clock. On the gears adjacent to the twelve o'clock side, eccentric pins 22 are also attached at twelve o'clock, and on the gears adjacent to the six o'clock side eccentric pins 23 are attached at six o'clock. The dogs 8 are fitted to the twelve o'clock pins in each group, and also to the six o'clock pins in each group. The pins are of equal eccentricity throughout. The racks 6 which extend from one end of the section to the other, are supported as already described, and they are meshed with the respective groups of gear-units. 40 45 50 55 The ends of the racks 6 which extend outside the

section have recesses which engage with flanges 24 on the adjusting screws 13. If the racks are adjusted so that the gear-units rotate in clockwise direction, the dogs 8 connected to the pins at twelve o'clock will move bodily towards the plates on the right hand side, and the dogs connected to the pins at six o'clock will move bodily towards the plates on the left hand side.

The back marginal space may thus be determined and modified with facility and exactitude, and eight plates can be released for removal; also eight replacements can be fixed exactly in position by the adjustment of one screw or by other means.

Means are provided for straight line movement of the dogs 25 on the fore-edge side of the plates by a twin-gear mechanism.

The outer or fore-edge dogs 25 are attached to two spaced dovetailed sliding components 26, 27 sunk flush in the upper surface of the subsections. The centre line of each sliding component runs through the centre of the gear-unit which actuates it. The eccentric pins 28 operate in the slots in the sliding components whereby to cause straight line movement of the sliding components. The gear units which actuate the fore-edge dogs 25 are actuated by the rack 6 at each side of the subsection, and each rack 6 is adjusted by one screw 13, substantially as described for the triple-gear mechanism. To facilitate assembly of the gear units in their bearings, the rack 6 must be withdrawn from mesh, a series of small eccentrics 29 being located on the cross-bars to make the adjustment. Situated about half-way along the length of each of the fore-edge dogs is or are one or more projections 30. These projections 30 are so shaped that they can engage easily with notches cut in the side of the plates P. These notches are cut in a position to determine the desired proportions of the head and foot margins. This provision is made so that plates with a head to foot dimension less than the standard size plates can be used. The head to foot dimension of the standard size plate is such that they will be maintained in position by the cross bars or by projections fitted to the cross bars.

The arrangement for a twin-gear device is shown in Fig. 8. The chief difference between the two arrangements is that in the triple-gear arrangement the movement of two dogs is maintained in parallelism in opposite directions by the gears, whereas in the twin-gear arrangement the

movement of each dog is maintained in parallelism by two gears.

The actuation of the two-unit gears may be performed by a rack on one side only by arranging the eccentric pins in a twelve o'clock or six o'clock direction as required for the movement of the dogs; or, if preferred, racks may be fitted on each side of the twin gears.

The control and adjustment of these racks for the twin-gear method is similar to that for the triple-gear method.

What I claim is:

1. A mechanical mount for the assembly of flat printing right hand plates and left hand plates 15 constituting at least one unit section, parallel racks incorporated in said section, and movable endwise of said section, the middle one of said racks being movable between back marginal edges of right hand plates and back marginal edges of left hand plates, and the left-hand and right-hand racks being movable adjacent to the fore-edges of the respective plates, gear pinions incorporated in said section and engageable by said racks, eccentric pins carried by said pinions, and plate-edge-clamping dogs each operatively connected to two eccentric pins, said middle rack engaging sets of pinion for rotating eccentric pins whereby to move dogs bodily into clamping engagement with the back marginal edges of both right-hand plates and left-hand plates.

2. A mechanical mount for the assembly of flat printing right hand plates and left hand plates 35 constituting at least one unit section, parallel racks incorporated in said section, and movable endwise of said section, the middle one of said racks being movable between back marginal edges of right hand plates and back marginal edges of left hand plates, and the left-hand and right-hand racks being movable adjacent to the fore-edges of the respective plates, gear pinions incorporated in said section and engageable by said racks, eccentric pins carried by said pinions, and plate-edge-clamping dogs each operatively connected to two eccentric pins, said middle rack engaging sets of pinions for rotating eccentric pins whereby to move dogs bodily into clamping engagement with the back marginal edges of both right-hand plates and left-hand plates, one pinion of each of said sets carrying a pair of eccentric pins, said pair of eccentric pins engaging a pair of dogs.

JOHN MURRAY.
